FENCE SECTION AND POST COMBINATION

Robert Grubbs, P.O. Box 1153, Boron, Calif.

Filed May 28, 1959, Ser. No. 56,117

Term of patent 14 years

(Cl. D28—1)

Fig. 2 is a vertical cross-sectional view thereof taken on line 2—2 of Fig. 1.

Fig. 3 is a fragmentary transverse cross-sectional view thereof taken on line 3—3 of Fig. 1.

I claim:

The ornamental design for a fence section and post combination, substantially as shown and described.
